CLAIM

The ornamental design for a interfitting container, as
shown and described.

DESCRIPTION

FIG. 1 is a perspective view of a interfitting container
showing my new design;

FIG. 2 is a perspective view of bottom and sides
thereof;

FIG. 3 is a bottom plan view thereof; the top plan view
being a mirror image;

FIG. 4 is a left side elevation thereof; the front elevation
being the mirror image; and

FIG. 5 is a right side elevation thereof; the rear elevation
being a mirror image.
